US00D856814S

(12) **United States Design Patent** (10) **Patent No.:** **US D856,814 S**
Villarreal et al. (45) **Date of Patent:** **** Aug. 20, 2019**

(54) **COMBINED COSMETICS DISPENSER AND APPLICATOR**

(71) Applicant: **HCT GROUP HOLDINGS LIMITED**, Central (CN)

(72) Inventors: **Armando Villarreal**, Los Angeles, CA (US); **Stephen Charles Burditt**, Los Angeles, CA (US)

(73) Assignee: **HCT GROUP HOLDINGS LIMITED**, Hong Kong (HK)

(**) Term: **15 Years**

(21) Appl. No.: **29/588,745**

(22) Filed: **Dec. 22, 2016**

Related U.S. Application Data

(63) Continuation-in-part of application No. 14/796,075, filed on Jul. 10, 2015.

(57) **CLAIM**

The ornamental design for a combined cosmetics dispenser and applicator, as shown and described.

DESCRIPTION

FIG. 1 is a front elevation view the combined cosmetics dispenser and applicator showing the new design;

FIG. 2 is a right view thereof, the left view being a mirror image of the right view;

FIG. 3 is a rear view thereof;

FIG. 4 is a top view thereof;

FIG. 5 is a bottom view thereof;

FIG. 6 is a bottom view thereof; omitting the applicator surface for clarity;

FIG. 7 is a perspective view of the apparatus of FIG. 1, with a cap thereon; and,

FIG. 8 is a bottom view of the apparatus of FIG. 7.

The portions of the Figures shown in broken lines are included for purposes of illustration but form no part of the claimed design. The claimed design does not include the portion inside the dot-dash boundary of FIG. 6.

1 Claim, 8 Drawing Sheets
